POULTRY CAGE DIVIDER PANEL

Gerald L. Kitson, 9709 Belding Road,
Rockford, Mich. 49341

Continuation-in-part of design application Ser. No.
119,078, Feb. 25, 1971, now Patent No. 225,337.
This application Dec. 4, 1972, Ser. No. 311,915

Term of patent 14 years

Int. Cl. D30—02

U.S. Cl. D30—2

FIG. 1 is a front elevational view of a poultry cage divider panel embodying my new design;

FIG. 2 is a right end elevational view; and

FIG. 3 is a top plan view.

This application is a continuation-in-part of my co-pending application Ser. No. D. 119,078, filed Feb. 25, 1971, now Pat. No. D. 225,337.

I claim:

The ornamental design for poultry cage divider panel, as shown.
